CRUDE OIL BURNER

Filed Feb. 20, 1930

INVENTOR.
Heberto Gavino
BY *Soltau Polachek*
ATTORNEY

UNITED STATES PATENT OFFICE

HEBERTO GAVIÑO, OF TOLUCA, MEXICO

CRUDE OIL BURNER

Application filed February 20, 1930, Serial No. 429,866, and in Mexico March 2, 1929.

This invention relates to new and useful improvements in a crude oil burner.

The invention has for an object the provision of a device of the class mentioned which is of simple, durable construction, dependable in use and efficient in action, and which can be manufactured and sold at a reasonable cost.

The invention proposes a cross pipe fitting 10 plugged at one end and threaded at the diametrically opposite end for connection with a steam pipe, a nozzle engaged in one of the remaining ends of said fitting, an atomizer pipe support engaged in the other end and adapted for connection with a fuel supply, an atomizer pipe supported in said support, and means for holding the said atomizer pipe in various adjusted positions relative to the nozzle. The invention also proposes means 20 for locating the position of such atomizer pipe from the exterior of the burner.

This construction presents various advantages, one being that the adjustment of the atomizer pipe is internal to the burner. Further, it is a very simple apparatus without complications in its system of atomization, and is adapted to any boiler that burns crude oil under pressure of steam, whether stationary, portable or of the marine type. The 25 tubes for conducting the steam and the crude oil are independent from one another so that no clogging can occur.

The atomizing system of the burner burns the crude oil immediately as it comes out of 30 the nozzle producing a column of fire from four to six meters in circumferential length without material expansion. The flame is white and not red as with common burners, and it is especially adapted for railroad boilers. It does not produce any smoke, and if 35 any, of a very insignificant density which shows that complete atomization of the crude oil takes place and therefore a considerable economy of fuel in comparison with common 40 boilers generally used. It is extremely useful for boilers that have to maintain a constant high pressure due to density of the heat that it produces.

This boiler also has various advantages 50 over the burners of modern boilers, such as

the production of high heat, the system of atomizing crude oil under steam pressure, a complete atomization of the crude oil, non-clogging as sand or other particles of foreign matter deposited in the fuel tanks, does not require high pressure pumping as all other burners used at the present time.

A further advantage is that it does not need to be cleaned every two to four hours, not even when the oil is dirty, as once the burner is adjusted to the boiler and the fire regulated it will not have to be removed as it will not require cleaning owing to the fact that the blowing of the steam will sweep out all that may be inside once the conduit of the crude oil is closed, as that is taken out from the vacuum, does not form carbon in the form of a cone as do many present burners that are in use, which interferes with the flame, no residue is left in the fire pit because all the crude oil is completely burned as it passes, and produces no smoke, uniformity of heat keeps the steam pressure always uniformly maintained, and it has great economy of fuel, since complete atomization of the crude oil takes place.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a side elevational view of a burner constructed according to this invention.

Fig. 2 is a bottom view of Fig. 1.

Fig. 3 is a vertical sectional view taken on the line 3—3 of Fig. 2.

Fig. 4 is a fragmentary vertical sectional view taken on the line 4—4 of Fig. 3.

Fig. 5 is an enlarged detailed view similar to a portion of Fig. 3 but illustrating a modification.

Fig. 6 is a vertical sectional view taken approximately on the line 6—6 of Fig. 5.

Fig. 7 is a vertical sectional view taken on the line 7—7 of Fig. 5.

Fig. 8 is a fragmentary view similar to a

portion of Fig. 1 but illustrating another embodiment.

Fig. 9 is a view similar to Fig. 8 but illustrating a still further embodiment.

5 Fig. 10 is an enlarged vertical sectional view taken on the line 10—10 of Fig. 9.

The crude oil burner consists of a cross pipe fitting 10 plugged at one end 11 and threaded at the diametrically opposite end 12 for connection with a steam pipe, a nozzle 13 engaged in one of the remaining ends of the fitting, namely end 14, an atomizer pipe support 15 engaged in the other end 16 and adapted for connection with a fuel supply, an atomizer pipe 17 supported on said support 15, and means for holding said atomizer pipe in various adjusted positions relative to the nozzle 13.

The three open ends of the cross pipe fitting 20 are formed with pipe threads. The inner end of the nozzle 13 is threaded for engaging the pipe threads of the fitting and is formed with a shoulder 18 for abutting against the outer face of the fitting. The atomizer pipe 25 support 15 is also formed with pipe threads engaging the threads in the open end 16 of the cross pipe fitting and is formed with a flange 19 abutting against the outer surface of the end. The atomizer pipe support 15 is 30 also formed with a hexagonal portion 20 for receiving a wrench or other turning tool so that it may be tightly engaged in place. Indicating arrows 21 show the path of the steam, and indicating arrow 22 the path of the crude 35 oil. The nozzle 13 has an inner converging passage 23 connected with an outer flared portion 24.

The atomizer pipe support 15 is also provided with a pair of spaced lateral lugs 25 40 for receiving a supporting pin from a control system not shown on the drawings. The inner end of the atomizer pipe 17 is threaded with screw threads and engaged in a threaded aperture extending thru the inner end of the 45 atomizer pipe support 15. The means for holding said atomizer pipe 17 in various adjusted positions relative to the nozzle 13, consists of a nut 27 engaged upon the threads of the pipe 17 and abutting against the pipe support 15.

In the modified form of the device illustrated in Figs. 5 to 7 inclusive, a means has been shown for holding said atomizer pipe 17 in various adjusted positions relative to the 55 nozzle and consists in longitudinal ribs 28 formed upon the atomizer pipe and engaging thru grooves in the pipe support 15 so as to be slidable. The inner end of the pipe 17 is formed with a piston portion 28^a encircled 60 by a packing bushing 29 arranged to be a tight fit within the pipe support 15. The inner end of the piston portion 28 is flared as indicated by reference numeral 30. One of the ribs 28 is formed with rack teeth 31 engaged by a gear 32 fixed upon a spindle 33

rotatively extending thru the pipe fitting 10. A hand wheel 34 is fixed upon the outer end of the spindle 33 for manual operation to cause the atomizer pipe 17 to assume various adjusted positions.

In the modified form of the device illustrated in Figs. 9 and 10, a means has been disclosed for locating the position of the said atomizer pipe from the exterior of the burner and consists of a plurality of plungers 35 arranged in a longitudinal row upon the nozzle 13 and extending into the interior. Each of these plungers consists of a stem 36 slidably engaged thru the nozzle, a head 37 on the exterior of the stem, a cross pin 38 thru the stem and within the nozzle, and an expansion spring 39 acting between the nozzle and the head 37 for normally urging the stem 70 outwards. The atomizer pipe 17 is formed with a small longitudinal slot 40 of limited length so that one of the plungers 35 may be depressed for engaging within the slot and abutting against one or the other ends as the atomizer pipe is adjusted and so limit its 75 position from the exterior. If one of the other plungers is depressed, a different set of limiting positions is obtained.

In Fig. 8, another means has been shown for locating the position of the atomizer pipe 17 from the exterior of the burner, and particularly for use with the form of the device illustrated in Figs. 1 to 4 inclusive. This means consists of the plungers 35 similar to those previously described, but engageable in a spiral slot 40' formed in the atomizer pipe 15 so that the atomizer pipe may be rotated to various adjusted positions and the depressed plunger engaged against one of the ends of the spiral slot and thus limit its extended or retracted positions. The slots 40 and 40' do not extend thru the atomizer pipes but are only arranged slightly into its surface.

This burner is adapted to use oil known under the name of asphalt. It is adapted to atomize the asphalt oil and produce more of the combustible gas, therefore it is more economical in use. It does not consist of many parts so that it may easily be dismounted if it is necessary. The burner may be formed of various sizes for adaptation to any boiler no matter of what design. The nut 27 may be loosened and the atomizer pipe 17 adjusted relative to the nozzle 13, and then the nut 27 tightened back into its place for maintaining the new position. In the form shown in Figs. 5 to 7, the hand wheel 34 may be rotated for accomplishing the adjustment of the atomizer pipe.

While I have shown and described the preferred embodiment of my invention, it is to be understood that I do not limit myself to the precise construction herein disclosed and the right is reserved to all changes and modi- 125 130

ifications coming within the scope of the invention as defined in the appended claims.

Having thus described my invention, what I claim as new, and desire to secure by United States Letters Patent is:—

- 5 States Letters Patent No. 1,000,000
1. A crude oil burner, comprising a cross
10 pipe fitting plugged at one end and threaded
at the diametrically opposite end for connec-
tion with a steam pipe, a nozzle engaged in
one of the remaining ends of said fitting, an
atomizer pipe support engaged in the other
15 end and adapted for connection with a fuel
supply, an atomizer pipe supported on said
support, means for holding said atomizer
20 pipe in various adjusted positions relative to
the nozzle, and means for limiting the posi-
tion of said atomizer pipe from the exterior
25 of the burner, comprising a plurality of
plungers in a longitudinal row mounted thru
said nozzle and upon depression engageable
30 in a slot of limited length formed in the said
atomizer pipe.
2. A crude oil burner, comprising a cross
35 pipe fitting plugged at one end and threaded
at the diametrically opposite end for connec-
tion with a steam pipe, a nozzle engaged in
40 one of the remaining ends of said fitting, an
atomizer pipe support engaged in the other
45 end and adapted for connection with a fuel
supply, an atomizer pipe supported on said
support, means for holding said atomizer
50 pipe in various adjusted positions relative to
the nozzle, and means for limiting the posi-
tion of said atomizer pipe from the exterior
55 of the burner, comprising a plurality of
plungers in a longitudinal row mounted thru
said nozzle and upon depression engageable
60 in a slot of limited length formed in the said
atomizer pipe, said plungers comprising a
65 stem and a head on the exterior of said stem.
3. A crude oil burner, comprising a cross
70 pipe fitting plugged at one end and threaded
at the diametrically opposite end for connec-
75 tion with a steam pipe, a nozzle engaged in
80 one of the remaining ends of said fitting, an
atomizer pipe support engaged in the other
85 end and adapted for connection with a fuel
supply, an atomizer pipe supported on said
support, means for holding said atomizer
90 pipe in various adjusted positions relative to
the nozzle, and means for limiting the posi-
95 tion of said atomizer pipe from the exterior
100 of the burner, comprising a plurality of
plungers in a longitudinal row mounted thru
said nozzle and upon depression engageable
105 in a slot of limited length formed in the said
atomizer pipe, and means for normally urg-
110 ing the plungers outwards, comprising a
coaxial expansion spring arranged on the
115 plunger and acting between the plunger and
the nozzle.
120 In testimony whereof I have affixed my
signature.
HEBERTO GAVIÑO.
